US00D803064S

(12) **United States Design Patent** (10) Patent No.: **US D803,064 S**
Marina et al. (45) Date of Patent: ** Nov. 21, 2017

(54) **BOTTLE**

- (71) Applicant: **PepsiCo, Inc.**, Purchase, NY (US)
(72) Inventors: **Carlos Hernan Marina**, Deerfield Beach, FL (US); **Dario Federico Stanziano**, Bueno Aires (AR); **Hernán Javier Giorgi**, Buenos Aires (AR); **Tomás Águila**, Buenos Aires (AR)
(73) Assignee: **PepsiCo, Inc.**, Purchase, NY (US)
(**) Term: **15 Years**
(21) Appl. No.: **29/567,996**

(22) Filed: **Jun. 14, 2016**

(51) LOC (10) Cl. **09-03**
(52) U.S. Cl.
USPC **D9/537; D7/511**

(57) **CLAIM**

The ornamental design for a bottle, as shown and described.

DESCRIPTION

FIG. 1 is a top front perspective view of a bottle showing the claimed design;

FIG. 2 is a bottom front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the bottle that form no part of the claimed design.

1 Claim, 7 Drawing Sheets
